UNITED STATES PATENT OFFICE.

KONRAD WINKENBACH, OF NEWARK, NEW JERSEY.

GRAINING TOOL.

Application filed January 31, 1925. Serial No. 5,928.

To all whom it may concern:

Be it known that I, KONRAD WINKENBACH, a citizen of the Republic of Germany, residing at Newark, in the county of Essex 5 and State of New Jersey, have invented new and useful Improvements in Graining Tools, of which the following is a specification.

This invention relates to improvements in 10 tools used by painters in producing on flat surfaces the appearance of longitudinally cut wood, or marble artificially simulating the natural markings, striations or grain thereof with more or less fidelity.

15 The operation of graining is usually performed by applying a flat color, constituting the background or base, with a brush and after this has set or become hardened, a darker color representing the veining produced by successive annular growths, this 20 color being applied with a comb-like tool in an irregular fashion and further distributed by dabbing with a rag or sponge to produce the desired effect, this process being crude 25 and accomplished satisfactorily only by an artistic and experienced workman.

It is also known that graining tools in the 30 form of a roller having handles at its ends have been used, the roller being provided with a sleeve circumferentially engraved to present the markings of a relatively short section of the desired graining, which is therefore necessarily duplicated at each 35 full revolution of the roller, or the roller may be cut in cameo itself.

Obviously several such rollers, bearing 40 different patterns may be used consecutively, but it is apparent that the loss of time in changing from one to another and the waste of paint is objectionable.

It is further to be noted that the handles 45 of such rollers prevent their use in interior corners and without the handles the implement cannot conveniently be used.

It is therefore the principal object of the 50 present invention to provide a graining tool of the roller type having a flexible sleeve so engraved as to produce different designs by various changes in its manipulation.

55 A further feature is in the provision of a roller having openings in its ends into which the fingers of an operator may be inserted to manipulate the same when conditions are such that the usual handles cannot be used.

55 Another aim is to produce a graining tool of roller type, having a flexible sleeve or

sheath and provided with handles at its ends so arranged as to be free to rotate upon their spindles, rigidly secured to the roller, or entirely removed at will. 60

These several features are accomplished by the novel construction and arrangement of parts hereinafter fully described and shown in the accompanying drawing, forming a material part of this disclosure, and 65 in which:—

Figure 1 is a perspective view showing a 70 framed panel and illustrating one manner of operating a roller made in accordance with the invention.

Figure 2 is a side elevational view showing a complete embodiment of the device.

Figure 3 is a central longitudinal sectional view of the same.

Figure 4 is a side view of the roller in 75 detail, partially broken away to show the construction.

Referring more particularly to Figure 1 of the drawing, a panel, designated by the 80 numeral 10, is shown as being surrounded by a raised frame 11, the face of the panel showing a grained finish as at 12 over a portion of its surface.

The roller, shown in detail in Figure 4 85 consists of a solid cylinder 14 of any desired uniform diameter, and of any suitable material, wood being preferred because of its lightness and ready availability.

In each end of the roller 14 are axial recesses 15 shaped to receive one of the fingers 90 of each of the hands of an operator whereby the roller may be manipulated over a surface as indicated in Figure 1, where, because of the raised elements 11, handles could not be used.

In ordinary practice however handles 17 95 are employed, the handles being of such shape and size as to be conveniently grasped by the hand and provided with a central bore 18 to freely rotate on spindles 19 having heads 20 and screw-threads 21 on their opposite, inner ends to engage directly in the ends of the roller at the bottoms 16 of the recesses 15.

The inner ends of the handles normally 100 abut the bottoms of the recesses and while free to turn on the spindles, may be clamped rigidly to the roller by turning the spindles, either one or both, to tighten the screws.

110 A sleeve 22 closely ensheathes the roller 14, this sleeve being made of resiliently yielding material, as rubber or a composition of

matter having similar properties, the sleeve being of considerable thickness and provided with raised corrugations 23 disposed over its entire circumference.

5 These corrugations are disposed in irregular formations, uniform in depth but varying in surface area and shape as well as in angularity with respect to the axis of the roller and to each other, and are also of different lengths.

10 In operation the paint to be used in graining is applied in any convenient manner to the outer surface of the sleeve, when assembled on the roller, which is then moved by means of the handles or otherwise in a direction generally lengthwise of the work surface.

15 It has been found in practice that the best results are attained by having one of the handles loose with respect to the roller and the other tight so that a combined rolling and sliding movement may be imparted to the roller, thereby producing a wide variety of designs wholly impossible to attain 25 by a roller which merely revolves upon its axis.

20 In addition to sliding movements, which are obviously limited in extent, the axis of the roller may be inclined upon its axis from time to time, and to different extents as 30 well as in opposite directions.

35 As a further feature advantage may be taken of the yieldability of the sleeve, different pressures producing unlike effects, because of the spreading of the corrugations, so that, due to the described structure and the different ways in which it can be manipulated, a limitless number of designs can be 40 produced with a single roller and without change of sleeve, although changes in the sleeve may be made in an obvious manner.

45 From the foregoing it will be seen that a simple device for this purpose has been disclosed in the preferred form of its em-

bodiment, but it is not desired to restrict the 45 details of the exact construction shown, it being obvious that changes, not involving the exercise of invention, may be made without conflicting with the scope of the appended claims.

50 Having thus described my invention, what I claim as new and desire to secure by Letters Patent, is:—

55 1. A graining tool comprising a solid roller containing finger receiving recesses in its ends, and a resilient sleeve on said roller said sleeve having an irregularly corrugated surface.

60 2. A graining tool comprising a solid roller containing an axial recess in each end, handles seated on the bottoms of the recesses, spindles adjustably threaded into the ends of said roller, said handles being rotatably mounted on the spindles, and a yielding sleeve directly fitting said roller, 65 said sleeve bearing a raised design.

70 3. A graining tool comprising a solid roller having an axial recess in each end, handles seated on the bottoms of the recesses, spindles on which said handles are 75 rotatably mounted, means whereby either of said spindles may be adjusted to clamp the corresponding handle rigidly to said roller, a resilient sleeve mounted directly on said roller, and a raised design on the surface of said sleeve, said design being composed of a series of irregular, angularly disposed, broken ridges of unlike area.

80 4. A graining tool comprising a solid roller containing finger receiving recesses in its ends, axially extending handles engageable in the recesses, means for securing either or both handles rigidly therein, and corrugated sleeves interchangeably engaged directly on said roller.

85 This specification signed this thirtieth day of January, 1925.

KONRAD WINKENBACH.
